RAILWAY SLEEPER

Jules Arnold Marie Delvaux, Brussels, Belgium,
assignor to Compagnie Internationale des Pieux
Armés Frankignoul, Liège, Belgium

Application September 13, 1945, Serial No. 615,984
In Belgium August 25, 1944

Section 1, Public Law 690, August 8, 1946
Patent expires August 25, 1964

8 Claims. (Cl. 238—117)

1

My invention is for improvements in or relating to hinged ties of concrete or the like particularly adapted for railway use although they can be equally well employed with all their inherent advantages as constructional girders for other purposes.

With the object of remedying the deformation of concrete and the like ties and to impart thereto a certain degree of flexibility, it has already been proposed to form a tie of a number of transverse elements or sections connected by one or more metal tie rods arranged to effect a longitudinal clamping action. On flexures of such a tie under the effect of the service loads, the edges of the successive elements wear away rapidly in consequence of the very large local compression stresses, thus producing a premature destruction of the tie, the elements of which have undergone such frequent relative transverse displacements. Furthermore, the flexibility of these ties was only negligible, the flexibility afforded by the tie rods in ordinary steel and moderately tensioned was insufficient to permit the elastic flexure of the tie with the amplitude provided for by official regulations, and giving furthermore rise to excessive fatigue of the tie rods.

The invention has for its object to provide a girder or tie capable of undergoing practically without fatigue repeated flexures of the desired amplitude, whilst ensuring the perfect elastic return of the tie to its normal position, as also its stable equilibrium in this position, so that permanent deformations of the girder need not be feared nor the local destruction or transverse relative displacement of its elements.

According to the invention, the object is attained by adjacent elements of the girder or tie which must be hinged together to bear normally one on the other by local members of contact which are provided on the adjacent faces of the elements of the tie and form for each direction of flexure provided for by the whole of the said adjacent elements of the tie, a hinge located externally of the axis of the stress developed by the longitudinal reinforcement placed under preliminary tension, which hinge is constructed in such manner as to be able to support the total stress of compression exerted on the elements of the tie. The adjacent extremities of the girder elements are preferably provided with projecting metallic plates which are embedded in the mass of the said elements, these plates being respectively provided with hollows and projections mutually fitting together and forming a hinge.

The number and the arrangement of the hinges

may vary according as to whether the tie is intended to undergo flexures in one or several directions. For each direction of flexure, there may be provided two hinges located on each side of the central axis of the force exerted by the longitudinal reinforcement, one or the other of these hinges intervening according to the direction in which the flexure takes place. These hinges may be made symmetrical or asymmetrical with respect to the said axis according as to whether the relative movement of rotation of tie elements is to be initiated for a single effort or for different efforts according to the direction of the flexure. The hinges also which correspond to different directions of flexure may be located at equal or unequal distances from this axis. Whatever may be the end section of the tie elements, it is sufficient to bring the hinges more or less close to the said axis to initiate the relative rotation of the tie elements under the effect of a more or less feeble effort.

In the case of flexures of a tie, it is the reinforcement which furnishes the flexibility ensuring the return into the position of rest of the tie. This reinforcement may be constructed in any suitable form, for example, it may be constituted by one or more longitudinal tie rods supported on the end elements of the tie. According to the invention, this reinforcement may be constructed of steel of high resistance and be placed under great preliminary tension, so as to be able to support without unallowable fatigue the repeated lengthenings and shortenings resulting from the flexures of the tie, or a spring or the like may be interposed between at least one extremity of the reinforcement and its support so as to cause a yielding displacement of the desired amplitude, practically doing away with the fatigue of the reinforcement which may then be made of a less elastic metal, for example a semi-hard steel.

Other features and advantages of the invention will appear from the description of some examples of embodiment which will be hereinafter described.

The invention will be hereinafter more particularly described with reference to the accompanying drawings, in which:

Figure 1 illustrates in plan a railway tie constructed according to the present invention with the reinforcement removed;

Figure 2 illustrates in section on the line II—II of Figure 1, a railway tie constructed according to the present invention, with the reinforcement in position;

Figure 3 illustrates on an enlarged scale in section on the line III—III of Figure 1, a fragmentary view;

Figure 4 illustrates an end view of the tie element located to the left in Figure 3;

Figure 5 illustrates an end view of a modified embodiment of a hinged tie element; and

Figure 6 illustrates a sectional view on the broken line VI—VI of Figure 5, together with a section of the adjacent element of the tie.

Referring to the drawings, the tie illustrated in Figures 1 and 2 comprises two raised end elements 1 and an intermediate element 2 which are made of reinforced concrete or the like and are connected together by a longitudinal reinforcement placed under preliminary tension. The reinforcement may comprise one or more tie rods 3 extending freely through longitudinal recesses 4 and 5 formed in the elements 1 and 2 and anchored with respect to the end elements 1 of the tie to which they are secured for example by means of nuts 6 and washers 7. Each tie rod 3 may comprise a single bar or a bundle of steel wires. In the example illustrated, a spring 8 is interposed between the extremity of each tie rod and the corresponding extremity of the tie, which permits the tie rods to be formed of semi-hard steel whilst ensuring that the rod yields sufficiently. The springs 8 may in particular be constituted by elastic washers in current use on railways.

The elements 1 and 2 of the sleeper are connected together according to the invention by hinged articulations 9, two embodiments of which are illustrated in the drawings.

In the example illustrated in Figures 3 and 4, each articulation comprises two metal plates 10, 11, embedded respectively in a raised end element 1 and in the intermediate element 2. One of the plates is provided with semi-circular ribs 12 which fit into corresponding grooves 13 of the other plate. The effect of the tie rods 3 is to draw the ribs 12 into the grooves 13, so that the assembly formed by the raised end elements and the intermediate element is maintained in stable equilibrium.

On a flexure of the tie the sections 1, 2 rock one with respect to the other about one or the other of the ribs 12 according to the direction of the stress, and return into position under the action of the tie rods as soon as the applied stress is released. There is thus produced a tie with double-hinged articulation and yielding return. It is obviously necessary to leave between the parts of the plates 10, 11 located outside the hinges, a space sufficient to permit the relative angular movement of the elements 1 and 2.

Whatever may be the direction of the flexure, the whole of the energy stored in the reinforcement by reason of the elongation of the tie rods or the like and/or of the compression of the spring or springs 8 is available to ensure the immediate yielding return of the tie into its position of equilibrium.

In the modification illustrated in Figures 5 and 6, the articulation is formed by two plates 14, 15 which are embedded in the elements 1 and 2 and have each four semi-spherical recesses 16, 17 in which are located four balls 18. These latter may be simply placed in the recesses 16, 17 or they may be fixed to one of the plates and located freely in the corresponding recesses of the other plate. The whole is kept in compression by a tie rod 19 placed in tension which ex-

tends freely through a bore 20 made in the tie elements and the plates 14, 15.

According as they are working in horizontal or vertical pairs, the four balls 18 form horizontal or vertical hinges permitting the relative hinging of the elements 1 and 2 in the vertical or horizontal direction. The same result would be obtained by four hinges similar to those shown by Figures 3 and 4 and formed by ribs and grooves arranged in a square or rectangle.

The modification according to Figures 5 and 6 is particularly useful for a railway tie which, apart from the vertical resultants of the differential loads transmitted to it by the two lines of rails, would have to withstand differential horizontal stresses due, for example, to braking actions.

The number of hinges of the articulation may be increased in such manner that for a tie or girder intended to undergo flexures in different directions, there is a hinge for each direction of flexure.

What I claim is:

1. An articulated tie comprising a plurality of separable elements arranged in end to end relation, a pair of mutually facing rigid contact members on the adjoining ends of at least two adjacent elements, longitudinal reinforcement means fixed relative to the end elements of the tie and extending freely through all of said elements and contact members and arranged under tension to apply a compressive force lengthwise of the assembly, and hinge means for each direction of flexure between the contact members of each pair of mutually facing contact members, each hinge means being arranged externally of the axis of the reinforcement means so that each hinge means permits flexure of the adjacent tie elements about a determined corresponding distinct axis located externally of and perpendicular to the axis of the reinforcement means, and the adjacent tie elements and contact members being slightly spaced from each other at points externally of each hinge means.

2. An articulated tie as claimed in claim 1, wherein each hinge means is constituted by a portion of one of the members of each pair of mutually facing contact members fitting into the adjacent facing contact member.

3. An articulated tie as claimed in claim 1, wherein each hinge means is constituted by a projection on one of the members of each pair of mutually facing contact members, engaging in a correspondingly shaped depression of the adjacent contact member.

4. An articulated tie as claimed in claim 1, wherein each hinge means comprises a metallic semi-cylindrical rib projecting from one of the contact members and the other related contact member having a groove of corresponding configuration provided in the adjacent face thereof for receiving the rib.

5. An articulated tie as claimed in claim 1, wherein each hinge means comprises two pairs of mutually facing semi-spherical recesses provided in two adjacent contact members and a ball of high resistance material located in each pair of mutually facing recesses.

6. An articulated tie as claimed in claim 1, wherein each hinge means comprises two semi-spherical recesses provided in each of the adjacent contact members and two balls located in said recesses, and each ball being fixed in one of the latter recesses.

7. An articulated tie as claimed in claim 1,

having hinge means of the same articulation of the tie arranged at different distances from the axis of the reinforcement means.

8. An articulated tie comprising a plurality of separate elements arranged in end to end relation, a pair of mutually facing rigid contact members on the adjoining end of at least two adjacent elements, a longitudinal reinforcement rod fixed relative to the end elements of the tie and extending freely through all of said elements and contact members and arranged under tension to apply a compressive force lengthwise of the assembly, and hinge means for each direction of flexure between the contact members of each pair of mutually facing contact members, each hinge means being arranged externally of the reinforcement rod so that each hinge means permits flexure of the adjacent tie elements about a determined distinct axis located exter-

nally of and perpendicular to the reinforcement rod, and the adjacent tie elements and contact members being slightly spaced from each other at points externally of each hinge means.
